UNITED STATES PATENT OFFICE.

IVES A. MILLER, OF GRAPEVILLE, PENNSYLVANIA.

RAIL-TIE.

1,092,073.

Specification of Letters Patent. Patented Mar. 31, 1914.

Application filed May 7, 1913. Serial No. 766,132.

To all whom it may concern:

Be it known that I, IVES A. MILLER, a citizen of the United States, residing at Grapeville, in the county of Westmoreland and State of Pennsylvania, have invented new and useful Improvements in Rail-Ties, of which the following is a specification.

The present invention relates to rail ties, and has for one of its objects to provide a reinforced plastic tie with metallic members which are embedded therein, and which serve as additional reinforcements, and project a slight distance above the tie to form seats for the rail, the said seats having associated therewith removable means for sustaining the rails upon the seats against vertical or transverse movement.

A still further object of the invention is the provision of a reinforced plastic tie with metallic rail seats which have rail securing members associated therewith, the said seats being disposed away from each other and out of contact with the metallic reinforcements for the tie to prevent the short circuiting of an electric current flowing through the rails or from an electric conductor connected with the joints or meeting ends of the rails.

A still further object of the invention is the construction of a plastic tie which has its lower and a portion of its side faces arranged within a woven wire basket, the said basket being flush with the said sides and bottom of the tie, reinforcements for the tie being arranged therein between the mesh basket, and the tie having embedded therein and projecting above its upper or top face metallic rail seats, the metallic basket adapted to protect the sides and bottom of the tie when the tie is tamped within the roadbed, and also adapted to prevent the disintegration of the tie from the moisture of the roadbed.

A still further object of the invention is the construction and arrangement of metallic rail seats which are embedded within a plastic tie, and which are so shaped as to provide reinforcing elements for the tie, and which, when embedded within the tie will so support themselves as to prevent movement, with respect to the tie in any direction.

With the above recited objects in view, and others which will appear as the nature of the invention is more fully understood, the improvement resides in the construction,

combination and arrangement of parts set forth in the following specification and falling within the scope of the appended claims.

In the drawing there is illustrated a satisfactory reduction of my improvement to practice, and in which drawing:

Figure 1 is a sectional view on the line $x-x$ of Fig. 2, Fig. 2 is an enlarged sectional view taken approximately on the line $y-y$ of Fig. 1.

My improved tie is formed of plastic material which is tamped within a suitable mold. In constructing the tie, I first place in the bottom of the mold a substantially rectangular reticulated or mesh basket 1 which is of a size and shape corresponding with that of the mold, and as a consequence rests upon the bottom of the mold and engages the sides, and if necessary, the ends of the mold. The basket 1, in all instances, has its bottom and sides running the full length of the mold, and the upper portions of the sides, and if desired the ends of the basket are bent inwardly, as at 2, the said inturned portions or flanges being only sufficient to receive the body of the plastic tie and to retain the sides, ends and bottom of the said basket flush with the sides, ends and bottom of the tie. The tie which is designated 3 by the numeral 3, is provided, a suitable distance above its bottom, with a plurality of longitudinally extending reinforcing rods 4.

During the process of molding the tie I arrange within the mold, adjacent the opposite ends thereof, metallic rail seats 5, preferably two of the said seats being disposed at each of the ends of the mold, and these seats are adapted to have their upper faces disposed a slight distance above the upper face of the tie, so that the rails arranged upon the seats will not contact with the body of the tie. The seats 5 each comprise a substantially rectangular member which provides straight sides and ends and horizontally straight bearing faces and bottoms. The lower edges of the members 5 are formed at their corners with outwardly extending flanges 6, and these flanges prevent the vertical movement of the said members 5 when the tie is molded, while the vertically straight sides and ends prevent either the longitudinal or lateral movement of the said seats.

In order to reinforce the upper portion of the plastic tie 3 between and to the opposite ends of the metallic seats 5, I employ longi-

tudinally extending bars 26 which have certain portions of their lengths arranged adjacent the top and corners of the tie but which are bent angularly, as at 27, a distance from the opposite ends of the members 5 and continued longitudinally, as at 28, below the said members 5. Any number of the members 26 may be employed, but none of the said members contact with each other nor with any of the members 5. This is important for the reason that it is not only desirable but essential that the tie and the members arranged upon the tie shall not interfere with a current of electricity conducted by the rails.

Having thus described the invention, what I claim as new is:

1. The herein described construction of ties including a plastic body having its bottom, its sides and ends incased in a metallic mesh basket, the edges of the basket entering the said sides and ends, metallic rail seats having their lower corners formed with flanges arranged within the tie, the upper portions of the seats projecting above the upper face of the tie, and rail securing members for the seats.
2. A tie comprising a plastic body, a bas-

ket comprising a foraminous metallic member arranged to receive the bottom of the tie and lying flush with said bottom and a portion of the sides and end of the tie, the basket having its upper edges inturned and embedded within the tie, longitudinal reinforcing members within the tie and disposed above the bottom of the basket and out of contact with the basket, substantially rectangular tie reinforcing members providing rail seats arranged within the tie above the basket, and rail securing members associated with the seats.

3. A plastic tie having metallic reinforcing members which are spaced from contact with each other and including rail seats having rail securing members associated therewith and having a foraminous member which is arranged flush with the bottom and with a portion of the sides and ends of the tie.

In testimony whereof I affix my signature in presence of two witnesses.

IVES A. MILLER.
